UNITED STATES PATENT OFFICE.

WALTER WRIGHT, OF NEW YORK, N. Y., ASSIGNOR TO ADDRESSOGRAPH COMPANY, OF CHICAGO, ILLINOIS, A CORPORATION OF ILLINOIS.

PRINTING-MACHINE.

1,203,678.

Specification of Letters Patent.

Patented Nov. 7, 1916.

Application filed October 27, 1910. Serial No. 589,405.

To all whom it may concern:

Be it known that I, WALTER WRIGHT, a citizen of the United States, and a resident of New York city, borough of Manhattan, 5 State of New York, have invented a new and Improved Printing-Machine, of which the following is a description.

The present invention relates to printing machines, more particularly to that class of 10 type and ribbon printing machines, designed primarily for producing quantities of facsimile typewritten letters, in which the body portion or subject matter of each is the same, and upon each of which a different 15 name and address is inserted, giving each one the appearance of an individually type-written letter, written specially to the person or firm to whom it may be addressed.

One of the objects of my present invention 20 is to produce a printing machine of this general character which shall be simple, inexpensive in construction and efficient in operation, and by which the user is not only enabled to produce perfect fac-similes of 25 typewritten matter, or work having the actual appearance and effect of ordinary type-writing, but is also enabled to print from type faced matter to which the ink may be applied directly, thus giving the product 30 the appearance of printed matter.

A further object is to provide means whereby two or more colors may be successfully used at one time, and at a single operation of the machine, one or more of 35 which colors may be taken from an inking ribbon, or ribbons, and impressed at any desired part of the letter, giving it the appearance and effect of having been written on an ordinary typewriting machine, while 40 another color may be applied directly to the face of the type or to a stereotype of the autographic signature of the writer, giving an entirely different appearance and effect.

A still further object of my invention is 45 to provide means whereby different names and addresses, contained in specially formed holders, or upon plates, may be automatically and successively brought into position to be printed at the top of the letters, at or 50 during each complete operation of the machine, and the same afterward, automatically and successively removed from the machine, to make room for others.

A still further object is to provide means, 55 such as a magazine tray which is capable of

being charged with a quantity of holders of different names and addresses, from which, when placed in the machine, they will be automatically and successively taken and brought into printing position, and after 60 leaving printing position, be automatically and successively brought into position to be successively removed from the machine, and properly stacked in another magazine tray, identical in construction with the one from 65 which they were previously removed.

A further object of the invention is to provide a magazine or receptacle, in which quantities of name and address holders may be charged, so that they may be properly 70 locked and carried therein and protected from damage or destruction, and which can be used also as a drawer of a cabinet in which it will fit with the same precision, as into the shelves and slides specially provided for its reception in the machine itself.

A still further object of the invention is to provide a name and address holder or plate, which shall be simple, inexpensive in construction, and by which the user is enabled, when using the holder, to make corrections in the name and address, or to remove the type matter or any portion thereof from said holder, and insert any new type character or characters, or to place 80 85 therein an entirely new address, if desired.

A still further object is to provide means whereby an autographic signature may be impressed at the usual place, at the bottom of each letter as it is struck off, which signature shall have all the appearance of having 90 actually been written by hand.

A further object of this special construction of the chase, is to enable standard electrotypes, or grooved type chases to be placed 95 therein, and locked in the same manner as ordinary type matter.

A further object is to provide means for producing uniform fac-simile typewritten work, on full length or short lines of type, 100 such as occur in business correspondence, more especially in the last lines of a paragraph, or in the first line of a paragraph; the salutation, or the adieu, such as Yours very truly, etc.

On account of the sensitiveness of inking ribbons, and the length of the ordinary typewriter line, and the distance between the type of one line and the type of the next line, when the first or last line of a para- 110

graph is shorter than the others, and sometimes in the last line of a paragraph there are not more than one or two words, and unless special means are provided, these 5 short lines would ordinarily receive a much heavier impression from the printing roller, and the result would be a much heavier imprint upon this line than upon other lines of the letter, thus destroying its appearance 10 and showing defectiveness in the work.

In brief the objects of the invention may be said to be first, to produce fac-simile typewritten letters and the like; second, to produce such letters in different colors and 15 effect; third, to automatically insert different names and addresses; fourth, to impress upon the letter the autographic signature of the writer, and fifth to automatically change and insert the proper salutations, 20 such as "Dear sir," "Gentlemen—," etc., together with the date.

It is well here to premise that, while the construction and arrangement shown in the drawings to be hereinafter fully described, 25 illustrate a printing machine operable by hand, it will be apparent that it may, by slight modifications, be changed into a power driven machine, and I reserve the right to so modify it, and to alter and otherwise 30 amplify the parts in any manner that may be held to fairly fall within the spirit and scope of my invention. It will also be obvious that the inking device shown for applying ink to the signature roller may be 35 modified or a regular inking fountain substituted therefor, and that the signature plate may be replaced by a similar electro-type engraved or etched, or other printing faced matter substituted whereby a letter 40 head may be printed on the sheet, at the time the fac-simile typewritten body of the letter is produced, and I reserve the right to so modify it, and to so alter and otherwise 45 change the parts to effect this result without departing from the spirit or nature of my invention.

The invention consists of the novel features and combinations of parts to be hereinafter fully described and pointed out in 0 the appended claims.

In the accompanying drawings I have illustrated a preferred embodiment of my invention.

Figure 1, represents a side elevation of a printing machine embodying my invention. Fig. 2, is a sectional side elevation of the same, looking from the opposite side of the machine, the line of section being taken approximately along the inner face of the frame. Fig. 2^a, is a detail view of the means for feeding the name and address holders or plates to the machine. Fig. 2^b, is a detail side view of a detent and appurtenances for locking the upper roller or tumbler shaft over which the name and address holders

travel, and onto which said holders are successively seated for printing, said detent serving for slightly tipping the front or back of the said shaft, as hereinafter further referred to. Fig. 3, is a view similar to 70 Fig. 2, showing only the upper portion of the frame which is broken away at places to show the ribbon feed mechanism and the printing carriage for actuating same. Fig. 4, is a detail view of one part of the ribbon 75 actuating feed removed from the frame. Fig. 5, is a longitudinal sectional elevation of the ribbon actuating mechanism, a portion of the carriage being also shown. Fig. 5^a, is a detail sectional view taken on the line 80 Z Z of Fig. 3. Fig. 6, is an elevation of the upper part of the frame, illustrating diagrammatically the means for throwing the printing roller into and out of operative position. Fig. 7, is a detail perspective view 85 of the means for tripping or throwing the printing roll into operation. Fig. 8, is a similar view of one of the tripping members. Fig. 9, is a detail perspective view of the means for effecting adjustment of the 90 printing roll tripping means, whereby more or less pressure thereof may be imposed on the type. Fig. 10, is a plan view of the machine. Fig. 11, is an enlarged plan view of the carriage which carries the printing and 95 signature rolls, as well as other parts which co-act with parts on the stationary frame or bed of the machine. Fig. 11^a, is a longitudinal section taken through the signature roll and its bearings. Fig. 12, is a central 100 section of that portion of the machine where the name and address holders are moved into printing position, and others being fed to and ejected from the machine. Fig. 12^a, is a detail view of one end of one of the rollers, comprised in the name and address mechanism, showing two of the holders seated thereon. Figs. 13 and 14, are horizontal sections taken, respectively, above the planes of the name and address holders, 110 showing the means for lifting the latter into printing position, and for ejecting them afterward. Fig. 14^a, is a detail perspective view of a retaining device for locking the name and address holders while in position 115 to be lifted to printing position. Fig. 15, is a central section taken through the printing carriage. Figs. 16 and 17, are detail views illustrating, respectively, the means for locking the signature roll against movement, and for unlocking and throwing the same into operative position. Fig. 17^a, is a detail sectional view illustrating additional means for effecting adjustment of the printing roller, whereby its pressure upon the 125 type may be increased or lessened. Fig. 17^b, is a fragmentary view showing in plan, a cap that forms a closure for each of the guideways of the bearing boxes of the printing roller. Fig. 18, is a transverse section 130

5 taken on a line adjacent to and immediately behind the name and address carrying mechanism, showing the holders or plates in place therein, but the type removed therefrom. Fig. 18^a, is a detail sectional view taken on line *x* *x* of Fig. 18. Fig. 19, is a perspective view of one of the name and address holders. Figs. 20 and 21, respectively, are a bottom plan and an end elevation of the same. Fig. 21^a, is a perspective view of the type used in same. Fig. 21^b, is a perspective view of a trip device adapted for insertion in the end of one of the grooves of the name and address holders or plates 10 for engaging and automatically changing the salutations. Fig. 22, is a perspective view of a magazine tray for holding the name and address holders or plates as they are being fed into or ejected from the machine. Fig. 23, is a detail perspective view of the same showing retaining latches designed for locking the name and address holders therein when the magazine trays are removed from the machine, and which are automatically pressed outwardly when in the machine, to permit of the holders being fed thereto. Fig. 24, is a perspective view of one form of chase, for holding the body portion of the type matter. Fig. 24^a, is a 15 detail plan view of one end of a type holder, partially broken away to show the means for locking the type therein. Fig. 24^b, is a perspective view of the member for carrying the salutation. Fig. 25, is a longitudinal section taken through one of the supporting rolls for carrying the name and address feed chain or conveyer, showing the means for effecting lengthwise adjustment thereof. Fig. 26, is a similar view taken on the line 20 *w* *w* of Fig. 18. Fig. 27, is a detail sectional elevation taken on the line *y* *y* of Fig. 18, showing the means for effecting vertical adjustment of the name and address mechanism. Fig. 27^a, is a detail front view of the 25 mechanism for changing the salutation. Fig. 28, is a detail sectional view, showing particularly the outer guide track for the holders or plates as they are being brought to printing position and to the point of ejection. Fig. 29, is a similar view illustrating further the construction of track for holders or plates. Fig. 30, is a detail perspective view of one end of the rolls for supporting the name and address holders or plates. 30 Figs. 31 and 32 are diagrammatic views illustrating electrical means for giving audible indication that the holders or plates on the delivery tray have all, or nearly all been fed to the machine, and also for giving similar indication that the receiving tray has been charged or nearly charged with ejected holders or plates. Fig. 33, is a detail view illustrating mechanical means for giving such indication. Fig. 34, is a detail 35 sectional view of a portion of the grooved

type holding chase showing some of the type locked in the grooves.

Similar reference characters designate corresponding parts in all the figures of the drawings.

In said drawings, A designates the table or bed of the printing machine, which is herein shown supported on a suitable frame work B, carried on legs C, which legs are of such an elevation from the floor as to bring the printing carriage D, to the proper height to be easily and conveniently operated through a handle E, or other suitable hand or power device.

The table or bed in the case taken for 80 illustration comprises the side members 3, which are properly spaced apart by means of girts 4, which extend across from one side 3, to the other, and are secured thereto in any desired or convenient manner, and upon 85 which girts is supported a chase 5, which holds the type 6, of the body portion of the letter or other desired matter to be printed. The chase 5, has a flat bottom and surrounding side walls so that type may be set therein 90 and locked by quoins, or instead of this type the regulation electrotypes of same height as regular printers' type, etc., may be placed therein and similarly locked. The chase 5 on its underside is formed with end flanges 95 7 (best shown in Fig. 12) and one of the girts 4 is cut away, as at 8, and is further provided with an upwardly projecting flange 10, between which and a clamping bar 9, the depending flange 7 of the chase is 100 interposed, which bar 9 fits in the cut away portion of the girt 4, and, by means of set screws 11, serves to clamp the chase securely 105 in position on the table or bed of the machine.

In order to produce perfect impressions from the type matter, it is necessary that the face of the type should be perfectly level, that is the chase should be maintained in a true horizontal position with relation to 110 the table or bed A, and for that purpose I provide set screws 12, which pass through threaded openings in the girts and are located so as to align with the lower edge of flanges 7, adjustment of which screws serves 115 to effect a proper leveling of the chase and consequent leveling of the type.

The type composing the body portion of the letter or other matter to be printed may be of the ordinary kind, as shown clearly in 120 Fig. 12, and locked therein by quoins such as are commonly used for that purpose by printers, or they may be set in a grooved plate, to be hereinafter described, and the plate itself locked in the chase. I have 125 not deemed it necessary to show the quoins or locking means for either the type or the plate, as they are too well known and understood in the art of printing to need either 130 illustration or description.

Referring to Figs. 1 and 5, it will be observed that the side members 3, of the table or bed A, are formed with a laterally projecting flange 3^a, which serves as a track upon, and under which, wheels or rollers 13, journaled in the carriage D, travel during the operation of printing, said wheels being preferably housed in between parallel walls 14, 15, of which the latter extend 10 downward in such manner as to overlap the outer side of the side members 3. Within appropriate openings in the walls 15, are also journaled horizontally-disposed rollers 13^a, which contact with and ride upon the 15 outer surface 3^b, of the flange 3^a, thereby preventing lateral movement and consequent displacement of the carriage D, as well as serving to maintain it in proper relative position with the bed or table, after being 20 properly adjusted to the flanges or tracks 3^a, which adjustment is effected by means of eccentrically mounted studs 13^b, upon which the lower rollers 13, are mounted. The carriage D, supports a printing or pressure 25 roller 16, which, in this instance preferably takes the form of an ordinary platen used in typewriting machines, having a rubber or yielding covering 17, and a signature roll 18, is also carried by said carriage, having 30 an ink roller 19 (which may be replaced by a regular ink fountain if desired) for supplying ink thereto. Upon the carriage is also mounted, a locking means to be herein-after described, for holding the signature 35 roll 18, against rotation and for further assuring its proper relocking upon return to initial position after operation. The printing roller 16, is loosely mounted upon a shaft 21, the ends of which shaft are supported in eccentric bearings 22, carried in 40 boxes 23, (dotted lines Fig. 15) which are capable of up and down movement in guideways 24, formed in each of the side plates 15, of the carriage D. The journaled boxes 45 23, at their upper ends are provided with adjustable devices, for adjusting them, so as to cause the printing or pressure roller 16, to exert more or less pressure upon the type, as occasion or varying conditions may 50 require. These adjustable devices are herein shown as comprising screws 26, having reduced threaded shanks 27, adapted to enter threaded openings 27^a in the caps 28, which form a closure for the guideways 24. The 55 upper enlarged head 29, of each of the screws 26, receives upon it a nut 30, here shown as cylindrical in form and provided with an internal chamber 31, having a closed bottom 32, between which bottom and 60 the enlarged head 29 of the screw 26, is interposed a spring 33, the latter serving to keep the nut 30, seated on the cap 28; and the underside of the nut is provided with a pin 34, adapted to enter one of the series of 65 holes 35, formed in the cap 28. Each screw

26 is grooved lengthwise, as at 36, to receive a pin 37, projecting from the nut 30, the arrangement being such that the nut may be lifted so as to withdraw the pin 34, from the hole 35, thereby permitting of rotative movement thereof, which movement in turn effects rotation of the screw 26, in adjusting the boxes 23, so that the printing or pressure roller 16, may be properly leveled. Springs 25, interposed between the lower ends of 70 guideways 24 and the lower ends of the boxes 23, keep the latter in elevated position. It will be observed that the diameter of the pressure roller or roller platen 16, is such that the said roller makes more than a single 80 revolution while in contact with the paper sheet on each printing stroke.

Referring to Fig. 17^b, it will be observed that the holes 35, in the cap 28, are arranged in close relation to each other, and consequently the most minute adjustment of the printing or pressure roller 16, may be obtained upon either end, bringing it to a proper and true level throughout with the face of the type in the chase and also insuring the proper and required pressure thereof on the type, to effect the best results, as the carriage D, is moved thereover during the process of printing. The pin 37 prevents the screw 26 from "walking" and thus holds the printing roller in perfect adjustment. To the carriage D is secured, in any desired and convenient manner, a leaf or paper shelf 38, upon which the paper is placed, one sheet at a time, and from which it is fed to the action of the printing or pressure roller, said shelf being provided with an orifice or opening 39, through which the paper passes after receiving the impression from the type. The leaf 38, is here shown as a thin plate supported on brackets 40, projecting from the carriage D, and preferably occupying an inclined position, the lower end of said leaf being arranged to lie in close proximity to the printing or pressure roller 16, and beneath which is journaled a feed roller 41, which extends transversely of the carriage and impinges the periphery of the printing or pressure roller. This feed roller is supported in 100 swinging arms 42, depending from the side walls of the carriage and is held constantly pressed against the printing or pressure roller 16, by means of a spring 43. In order to effect proper alinement of the paper as it is delivered to the machine, I provide a gage plate 44, having a vertical wall 45, against which the edge of the paper abuts, and the adjustment of this gage is accomplished through the medium of screws 46, which pass through perforations in the gage 44, and also through elongated slots 47, in the leaf 38. The signature roll 18, is adjustably secured to a sleeve or tube 18^a, and is slidable thereon and locked in any pos- 115 120 125 130

tion by a clamp 18^b. The sleeve or tube 18^a is loosely mounted on a shaft 18^c, the ends of which are secured to eccentric journals 18^d, mounted in boxes 18^e, carried in slide-ways 18^f in the side plates 15 of the carriage D. Extending from the shaft 18^c, is a downwardly projecting extension or arm 56, the lower end of which, when the carriage is moved forward, is brought into contact with a pressure track 57, adjustably secured on the bed or frame of the machine, and directly in line with the arm 56. When the arm 56 comes in contact with one end of the track 57, it is swung or forced backwardly and upwardly, thus turning the eccentric journals 18^d, and thereby bringing friction rings 18^g on the sleeve or tube 18^a, into contact with the rubber face 17 of the printing or pressure roll 16, with which it rotates. The frictional pressure of these rings 18^g, against the rubber face 17 of the printing roller 16 will continue the rotation of the signature roll 18 so long as the arm 56 remains in contact with the track 57. The length of the track 57, equals approximately the circumference of the signature roll 18 and causes the latter to make one complete revolution, and when the arm 56 has passed over the other end of the track 57, it is turned backwardly and consequently the signature roll is moved away from contact with the printing or pressure roll 16. This backward movement of the arm 56 is effected by means of a spring 59, which is attached at one end to the arm 56, and at the other end to the frame of the carriage D. Upon one end of the sleeve 18^a, and adjacent to one of the rings 18^g, is fastened a disk 50 (Figs. 16, 17) having a notch 51 therein, to receive a tooth 52, formed on an arm 53, pivoted at 54 on an arm 55 extending from one of the eccentric journals 18^d. A spring 54^a presses said arm 53 against the face of the disk 50 during its rotation, so that the tooth 52 at all times has the tendency to enter the notch 51, and lock the disk against rotative movement when brought into register therewith.

As previously stated, the printing or pressure roller 16, is loosely mounted on the shaft 21, and to one of the eccentric bearings 22, carrying the same, is secured a downwardly projecting lever or arm 63, which is adapted to be rocked in either direction, by contact with either end of a track 63^a and which arm through the movement of the carriage, will be caused to ride on said track. The track which will be hereafter more fully described, is adjustably mounted at one side of the stationary bed or table, and causes the printing or pressure roller 16, through the rocking of the shaft 21 and eccentric bearings 22, to be pressed against the type faced matter, when the carriage D is moved in one direction,

and to be lifted out of contact and away from said type faced matter on the return movement of said carriage. The first use of the track is to trip the lever arm 63 so as to bring the printing or pressure roller 16, in contact with the rails 63^a, so that the printing or pressure roller 16 will be rotated by a forward movement of the carriage D, and thereby rotate the paper feed roller 41, thus carrying forward and around the printing roller 16, the letter head or sheet of paper then resting upon the paper shaft or feed table 38, so that it may be advanced any desired distance before the printing or pressure roller 16, comes directly in contact with the type faced matter on the bed or table of the machine. This is clearly illustrated in Figs. 6, 7, 8 and 9. The tripping tract 63^a is adjustable, both vertically and horizontally, and it will be observed that two parallel bars 64, and 65 are employed, both being adjustable longitudinally within a groove 66, of a holder 67, having on its underside inclined blocks 68, adapted to rest upon oppositely inclined blocks 69, projecting upwardly from a slide bar 70, the latter being slidably connected to one of the side members 3, of the bed or table of the machine. The end of each bar 64, 65, is split or slotted, as at 71, and is further provided with a threaded perforation to receive a tapered screw 72, by means of which the ends of the bars are spread apart and caused to grip the side walls of the groove 66, thereby clamping or holding them firmly in adjusted and desired position in the holder 67. The slide bar 70, has at each end, a guide block 73, adapted to move in guideways 74, in the side members 3, of the bed or table, and each block is provided with an elongated slot 75, to receive a shouldered screw 76 which passes therethrough and is secured in the bed or table. One of the guide blocks 73, has produced on, or secured to it, a lug or ear 77, (Figs. 6 and 9) through a threaded perforation in which is inserted the threaded end of a screw 78, fixed in the frame, and by turning said screw it will be obvious that the bar may be moved in one direction or the other, causing the blocks 69 thereon to move under the blocks 68, on the holder 67, lifting or lowering the latter, as the case may be, so as to give more or less turning movement to the eccentrics 22, thereby increasing or lessening the pressure of the printing roller on the typed matter contained in the chase. Obviously the lifting of the bar 67, so as to elevate the track 63^a, will give a greater turning movement or throw to the eccentrics 22 carrying the printing or pressure roller 16, consequently, more pressure will be brought to bear upon the type in the chase, while a reverse condition will be the result if the pressure track 63^a is brought to a lower ele-

vation. The return movement of the carriage D (illustrated diagrammatically to the right of Fig. 6) will bring the arm 63 into contact with the track 63^a, turning the eccentric bearings in an opposite direction, and thereby lifting the printing roller 16 away from the face of the type, as it passes over it. In both these instances the bars 64 and 65 and arm 63 raise or lower the printing roller, but the lever arm 63 while sliding along and over the track 63^a, will maintain the printing roller in its lowest possible position during the forward or printing movement of the carriage D, and in its highest position, or out of printing contact with the type during a return movement of the carriage D. The tracks 63^a, are also an important factor in the operation of the machine, as the eccentric arm 63, connected to the eccentric bearings of shaft 21, comes in contact with the rails 64 and 65, at a predetermined point in the forward movement of the carriage D, before the pressure roller can come in contact with the face of the type, so that the sheet of paper fed to the machine may be carried forward any desired distance before it comes in position to have the type matter printed thereon. Therefore, the first result of the trip or arm 63, in coming in contact with the rails 64 and 65, is to bring the ends of pressure roller 16, in contact with the two oppositely-disposed side rails 63^a arranged parallel and secured to the side members 3, of the bed or frame, and a further forward movement of the carriage causes the printing or pressure roller to rotate, and with it the feed roller 41, so that the sheet of paper then on the shelf or leaf 38, will be fed around the pressure roller any desired distance before coming in contact with the type faced matter on the bed or table of the machine. This is also for the purpose of giving the paper a perfect register, so that all sheets will have the printed matter inserted thereon, at the same marginal distance from the bottom and top of the sheet, and the printing will appear in exactly the same position on each sheet of paper. Any suitable or known expedient may be employed normally tending to restore the arm 63 to the vertical position; shown in Fig. 6, for this purpose is an arm 63^c, which is integral with arm 63, and has secured to it a retractile spring 63^h, the opposite end of which is secured to any fixed part of the carriage D, of which a fragment is indicated at the right of Fig. 6.

The operation of the mechanism for locking the signature roll against rotation, upon each complete rotation, and for unlocking the same for its next operation is as follows: When the arm 56 comes in contact with the forward end of the track 57, the shaft 18^c, through the eccentric journals 18^d, is rocked so as to bring the friction rings 18^e and the

signature roll 18, into contact with the printing roller 16. This action causes the arm 55, also mounted on the eccentric bearing, on the opposite end, to carry the arm 53, which is pivoted thereon at 54 forward, so that the inclined or cammed part 53^a, on its forward portion, rides over a rod 58 on the carriage D, far enough to lift the tooth 52, out of the notch 51, in the disk 50. As the carriage D continues its forward movement, the arm 53, will remain in its forward position, thus keeping the tooth 52 in its raised position and out of the notch 51, until such time as the arm 56 passes over the forward end of the pressure track 57, when the arm 53, under the pull of a spring 59 will be returned to its normal position, and the arm 53 will be drawn back, so that its inclined or cammed portion will return far enough to allow the tooth 52, to drop into the notch 51, at the time it completes its rotation, thus locking the disk 50 and signature roll 18 in their initial or starting points. The signature roll 18, carries a removable segmental plate 49, upon which may be engraved, or otherwise produced, the signature of the writer. The track 57 is slidable in a groove 57^b, in the bed or table and is so constructed that it may be raised or lowered, by means of locking screws 57^a, so as to register the signature at any desired marginal point of the letter or sheet, and the bearing boxes 18^e of the eccentric journals 18^d, carrying the signature shaft 18, have their rear surfaces tapered or inclined as at 18^h, against which the inclined surfaces of wedge pieces 18ⁱ bear, the latter being located in the guideways which carry the bearing boxes 18^e, and are adjustable up and down by means of adjusting screws 48, so as to enable the signature roll 18, to set closer to or farther away from the pressure roller 16. The rod 58, also supports what may be appropriately termed a paper guide, 60, which serves not only to direct the paper properly to the action of the printing or pressure roller 16, and feed roller 41, but also to guide it toward and through the opening or orifice 39, whence it passes to any convenient receptacle (not shown) arranged to receive it. This guide 60, is here shown as comprising a plate having upper and lower extensions 60^a, 60^b, respectively, the former being bent or arched over and above the printing or pressure roller, and the outer extremities project toward the orifice or opening 39 in the leaf 38, and the latter extension 60^b, pass under, and in close proximity to the printing or pressure roller, their ends terminating at a point below the feed roller 41. The guide plate 60, is slotted at 61, to permit the signature roller 18, to move into engagement with the printing and pressure roller, and extending from a point approximately contiguous to the lower edge of the slot 61, are down-

wardly projecting curved fingers 62, which serve as additional guides to properly guide the paper, should it sag or dip at any portion along its width.

5 The name and address plates or holders 79, consist of elongated plates herein shown as provided with three parallel grooves 80, to receive the type illustrated in Fig. 21^a. The number of grooves 80, however, may be 10 increased or lessened according to requirements, and each groove is formed approximately after the fashion of a dovetail, that is, its lower portion is enlarged to receive the enlarged base portion 82, of the type 82^a, 15 while the reduced shank portion 82^b, of the type passes in between the upper contracted side walls 83 of the grooves, which construction serves to keep the type in place after its insertion. Suitable means for locking each 20 line of type in the holder are provided, as shown at 80^c. These locks are herein shown as short springs which are inserted in the enlarged portions of the grooves 80, and which, when expanded therein effectually 25 lock the type.

The holder 79, is formed with laterally projecting legs or flanges 84, clearly illustrated in Figs. 19 and 21, against which the next succeeding holder 79, bears, the depth 30 of these flanges 84, being such as to prevent the bottom 79^a of one holder contacting with the face of the type contained in the other holder or holders, when they are assembled in position in magazine trays, in which they 35 are stored, and out of which they are fed to or received from the machine, thus any possible danger of damage to the face of the type is eliminated. The holders are further provided with end lugs or extensions 85, 40 which are recessed at 86, and upon the inner side walls of magazine trays 87, 87^a, ribs or rails 88 are provided, which are adapted to enter the recesses 86 in the holders 79, as they are successively arranged within the 45 trays. These lugs or extensions 85, are also for the purpose of seating and locking the name and address holders 79, on to an endless feed which is adapted to automatically, and in a step by step movement bring them 50 into printing position, so that the type in same is in the same parallel position as the faced matter in the chase, and, through means to be more fully described, the same are locked against movement while in printing position, so that perfect results may be 55 obtained at the same time the printing is being done from the permanent type faced matter in the chase.

It will be observed by referring to Figs. 60 22 and 23, that the ribs or rails 88, are tapered at one end 88^a to facilitate the insertion of the holders 79, and that their other ends 89 extend slightly beyond the end of the trays, and are tapered, the better to 65 guide the plates or holders 79 into the mag-

azine tray 87^a, as they are discharged or ejected from the machine. In order to retain the name and address holders 79 in the magazine tray 87, after their insertion therein, before or while they are being placed in the machine, I provide retaining devices 70 which are herein shown as spring hooks 90, and which, as shown in Fig. 22, are located at one end of the magazine trays 87, 87^a and which normally project into the path of 75 travel of the holders 79, thereby producing an effectual barrier against their accidental displacement or disarrangement. In the present machine I show two such trays 87, 87^a, which are identical in construction, and 80 interchangeable either or any of which without change, may be used to feed in or to receive name and address holders, which may have been fed to the machine and afterward ejected therefrom. Each tray is 85 formed of the longitudinal side bars having the described ribs 88, and end cross bars 87^b.

In the drawings I show one tray 87 which is used to hold a quantity of name and address holders 79 ready to be delivered to 90 the machine, and the other tray 87^a, which is located below the tray 87 to receive the holders 79 as they are ejected from the machine by means to be hereinafter described. The magazine trays 87, 87^a are placed in the 95 machine upon shelves 87^b, 87^c, the forward ends of which are secured to a frame or carriage 122 which is adjustably supported in a manner hereinafter described, and said holders are successively fed to the machine by mechanism comprising endless belts or conveyers 92, operated intermittently by means to be hereinafter described. Said belts pass over pulleys or rollers 93, 94, the pulleys or rollers 93 being journaled in end 100 plates 120, 121 of the frame or carriage 122, hereinafter further described, and the rollers 94 are secured to a shaft 93^a and so located with respect to the upper tray 87, 105 that the belts or conveyers will travel in a 110 plane slightly below the name and address holders 79, as the latter are carried forward on the side rails 88 of the tray 87, through the medium of a block or follower 95, movable with the belts or conveyers 92, and located behind the rearmost holder 79. The block or follower 95, has a slip connection with the belts 92, that is, the connection between them is such that the follower or block 95 will only be frictionally held so as 115 to move the name and address holders 79 in front of it, approximately the distance of the depth of one of the plates or holders, yet upon any excess movement of and consequent resistance given to the belt 92, the latter is caused to slip and therefore no further movement of the holders at that time can be effected. The object and purpose of this excessive movement is to insure at all 120 times that the name and address holders in 125 130

- the tray 87, will be carried far enough forward to properly insert and lock the foremost holder in the recesses formed on the links of the endless feeding chain of the machine, so that if at any time there should be a space between any of the holders 79, this excess forward movement of the follower 95, will take it up, or in case the belts or conveyers 92 have any excess movement over necessary travel, the slipping connection allows said belts or conveyers 92, to slip through the follower 95 after the name and address holders have been carried the necessary distance forward.
- Referring to Figs. 12 and 13, it will be seen that the block or follower 95, is an inverted U shaped bar of sufficient length to reach from one side of the tray 87 to the other, and in the ends of which are provided adjustable bearings 96, adapted to receive the ends of a rod 97, over which and under the rounded walls 98, of the follower 95, the belts 92 are passed. Adjusting screws 99 are provided which are adapted to enter threaded openings in the bearings 96, whereby the latter may be lifted to increase the tension on the belts, or lowered to decrease such tension as may be found desirable or necessary. While I have shown two endless belts or conveyers 92, it must be apparent that only one may be used in which event, of course, a wider belt would be employed, and again I prefer to interpose between the block or follower 95 and the rearmost name and address holder 79, an additional and removable bar 99^a, which is provided with suitable recesses 99^c, to receive appropriate headed pins or studs 99^b, on the forward upper part of follower 95, whereby connection between them is effected. The bar 99^a, has two legs 99^d, extending from its forward end which contact with the extreme ends of the name and address holders 79, at approximately the same point as the legs 84 on each holder, and these legs contact with the holder in front of it, so that they may be carried forward on the slide rails 88 of the tray 87, without any pressure or moving part coming in contact with the type face in the name and address holders. The bar 99^a, may of course be omitted, but I prefer to employ it for this purpose, as it is desirable that the follower should have some width, so as to prevent the possibility of side motion, or the feeding or forcing farther forward of one end of the name and address holders, slightly in advance of the other end, which might cause jamming in the feeding of same into the machine; and as it is also advisable and necessary at times to remove this follower from the magazine or feeding tray, after all the names and addresses therein have been fed into the machine, the part 99^a, can be readily lifted out, and the part 95, which is attached to the belts 92, can be carried around the rearmost pulleys and rollers 94 out of the way of the magazine tray, or in such a position that the tray 87 may be removed from the machine, and another tray 87 filled with name and address holders inserted in the machine. A crank handle 92^a (Fig. 2), is attached to the shaft on which the rearmost roller 93 is mounted and is for the purpose of effecting free movement of the belt or conveyer, at such time or times as the mechanism, to be hereinafter described, for automatically and intermittently moving it, is thrown out of operation, and for returning the follower 95, so that another magazine tray may be placed in the machine.
- At each side of the frame or carriage 122, adjacent to the delivering end of the tray 87, and of the recelying end of the tray 87^a, are arranged spring actuated catches or gates 100, 101 designed in one instance for the purpose of holding or clamping the name and address member after it has been advanced beyond the tray, and into position to be received by an endless and intermittently operated chain 102, and in the other instance to hold the name and address holders in the chain at the point of ejection, until they are positively ejected into the tray, by mechanism provided for that purpose, and also to prevent such name and address holders, after their ejection from the chain 102, on to the rails 88 of the tray 87^a, from falling backwardly toward the endless chain, or becoming otherwise displaced. The spring actuated catches or gates 100 and 101, are each formed with a tooth 103, 104, respectively, disposed in opposite directions to effect the results above described, and it will be observed by reference to Fig. 13, that the catches or gates 100, are each cut away as at 100^a, to provide an inclined or cam surface 100^b, which, when the tray 87, is placed properly in the machine, engages the beveled terminals of the hooks 90, forcing them outwardly to the position shown in Fig. 23, thus leaving the path of travel of the name and address holders to the chain 102, unobstructed.
- Springs 105 are placed on the reduced shanks of the catches or gates 100 and 101, their ends bearing respectively on the enlarged heads of the catches and against the end walls of the housings 105^a, containing the same, their tendency being to keep the catches or gates pressed outwardly and in position to perform the functions just described, and such outward movement is limited by means of pins 106, which project from the shanks of the catches or gates, and bear against the outer walls of the housing or other convenient part of the frame of the machine. The shanks of the catches 100 and 101 are each grooved longitudinally, as at 107, to receive a pin 108, which projects through a perforation in the housing, this

arrangement effectively preventing rotative movement of the catches and serving to maintain them in their proper operative position.

I will now proceed to describe the mechanism for automatically feeding the holders or plates containing the names and addresses into proper printing position there to be impressed on the letter, or other matter to be printed. On the inner portion of side members 3, are two vertical guideways 109, in which the end plates 110 of the supporting frame or carriage 122 are adapted to slide. Passing from one end plate 110 to the other, are the two rods 111, which are of approximately the same length as the width of the machine between the side members 3. On the side members 3, at the bottom of the guideways 109, there are brackets 112 secured thereto by screws 113 and extending inwardly therefrom are lugs or extensions, having threaded openings 114, in which are adjusting screws 115, the upper ends of which contact with the bottom 116, of the end plates 110 of the supporting frame, so that said plates may thereby be raised or lowered, and by lock nuts 117 the screws 115 are locked against further movement. In the side members 3, on the outside thereof, are additional clamping screws 118, which hold the frame fixed in adjusted position. Slidably mounted on the rods 111, are end plates 120, 121, of the carriage or slidable frame 122, upon which is supported the name and address holder feeding mechanism to be hereinafter described. Secured to the end plates 120, 121 are the plates or shelves, 87^b, 87^c, to the rear ends of which are secured side plates 127, 128, which are slidably supported upon a rod 129, the ends of which are secured in the side members 3. The shelves or plates 87^b, 87^c, as previously described, are adapted to support the magazine trays 87, 87^a, which contain the name and address holders 79, when they are inserted in the machine.

In the side plates 127, 128, are openings 130, adapted to receive sliding boxes 131, in which are bearings for the ends of the shaft 93^a to which pulleys or rollers 94 are secured. A threaded take up screw 132, collared in the ends of the side plates 127, 128, the threaded portion 133, of which goes through threaded openings in the sliding boxes 131, thus acting as adjusting or take-up screws for the endless feeding belts 92, and by means of which it is possible to tighten or loosen the tension on either of said feeding belts. Supported on the inside of end plates 120, 121, are tracks 134, which are separated by rods 135. Upon the tracks 134, the under portion of an endless sprocket chain 102 slides and between the end plates 120, 121, and the tracks 134, is a reduced portion 136, so as to permit the lugs or feet

84 of the name and address holders 79, to clear, so that the bottom 79^a, of the name and address holders 79, may be seated in the recesses or spaces, or on seats formed at the meeting ends of the links of the endless feeding chain 102. On the inner side of the end plates 120, 121, there are also flanges or raised portions 137, which, together with the blocks 134, form a guideway for the lugs 85, on the extreme ends of the holders 79, which, after a name and address holder is seated upon the endless feeding chain must, through operation to be hereafter described, travel through a fixed path with the endless sprocket feeding chain 102, before the said address holders can be removed from the chain.

The flanges or raised portions 137, of the guideway, are cut away at the front as shown at 138, at which point the name and address holders are fed in to the endless sprocket chain 102, and are ejected therefrom at 139, into a magazine tray 87^a, provided to receive them.

Formed in the forward extensions of the end plates 120, 121, are bearings 140 for a hollow shaft 141, secured to one end of which is a lever arm 142, and outside the opposite end plate 121, is a similar lever arm 143, both of which are secured to the hollow shaft 141 by set screws 141^a. The hollow shaft 141, has also secured to it a lever arm 144, the purpose of which, as well as levers 142, 143, will be hereinafter described.

Telescoping in hollow shaft 141, is a shaft 145, in which is a keyway 146, into which fits a key 147, made integral or secured to the hollow shaft 141. To the other end of shaft 145, is secured a rock arm 148. Secured to rods 111, is a bracket 151, which is held in a fixed position by screws 149, 150, and in which is a bearing 152 for the shaft 145 to rock in. A collar 153, secured by set screws 154, to the shaft 145, prevents any lateral movement of this shaft on the supporting frame. A wide bearing 155, in the upper portion of the bracket 151, supports rotatably, a hub or sleeve 156, secured to, or made integral with a combined locking and rotating wheel 157, located at the extreme outer end of the hub or sleeve 156. There are four notches 158, in said wheel, which through means hereinafter described, are adapted to lock said hub from rotation, while arms 159, are for the purpose of rotating same, by means hereinafter more fully described.

The inner end of the hub 156, is slotted as shown at 160, and is locked against lateral movement in bearing 155, by means of a collar 161, secured by set screws 162. The inner end of the collar 161, is threaded at 161^a, so that by means of a tapered clamping nut 163, the slotted portion of the hub may be clamped to a shaft 164, in which

- there is a keyway 165, into which a key 165^a, secured to the inner portion of the hub 156, is adapted to slide, so that the shaft 164, and hub 156, may be rotated as one solid shaft.
- 5 The movement of the sliding frame or carriage 122, to the left side of machine causes the shaft 164 to enter or telescope the hub 156, while, at the same time the shaft 145, will slide or telescope within the 10 hollow shaft 141. A clamping screw 166, in the hub 167 of the sliding carriage 122, serves to lock same against lateral movement, by pressure upon the rods 111, upon which the carriage 122 is supported. It will therefore 15 be seen that when the clamping screw 166, and tapered clamping nut 163 are loosened, the carriage 122 may be moved into any desired position laterally, and by again fastening the clamping screw 166, and nut 20 163, locked against lateral movement. The shaft 164, revolves and is supported in bearings 168, in the uppermost portion of the end plates 120, 121, of the carriage 122, and on said shaft between the bearings 168, is a 25 four sided printing block 170, upon the uppermost portion of which the bottom of the name and address holders sit, when in printing position.
- Mounted on the shaft 93^a, which carries 30 the rear pulleys or rollers 93, over which the endless feeding belts 92, travel, is a pinion 171, (see Fig. 2) the teeth of which mesh with a gear wheel 172, secured to which is a ratchet wheel 173, both of which are connected together to act as one, and are revolvably supported on a stud 174, secured in the side plate 121, of the carriage 122. A pawl 175, engages the teeth of the ratchet wheel 173, and is pivotally secured to a rocking arm 176, loosely mounted on the stud 174, said rocking arm being pivoted at 174^a, to one end of a link 177, the other end of which is pivoted to the downwardly projecting arm 144, secured to the hollow shaft 141.
- 40 45 An upstanding arm 180 secured to the shaft 145, has pivoted to it, one end of a link 181, the other end being pivoted to an arm 182, secured to a rock shaft 183, having bearings in the side frame 3, to which is also fastened 50 a double arm rocking lever or cam member 184, the latter occupying a position outside of, and adjacent to, the bed or frame of the machine, and being adapted for engagement with a stud or roller 185, projecting from 55 the side of the carriage D. The upper edge of this lever 184, is of such contour that, as the carriage is moved back and forth during the operation of printing, it will be caused to assume different positions, thereby rocking 60 the shaft 183 in one direction or the other, which, through the link 181 and other intermediate connections, just described, will give intermittent rotation to the ratchet wheel 173 and gear wheel 172, at the proper moment to impart rotative movement to the 65 pinion 171, and pulleys or rollers 93, and consequently cause an advance movement of the feed belts 92. Upon the hollow shaft 141 are also secured the two downwardly projecting arms 142, 143, which have a pin 70 and slot connection with ejectors 137^b, said ejectors comprising slotted plates having offsets 137^a, arranged to lie behind and in line with the lugs 84, of the name and address holders 79, so that a vibration of the 75 lever 184, will, at the proper moment, move the ejectors forward, and project a name and address holder past the catches 101 and hooks 90 on to the receiving tray 87^a. The ejectors move in grooves 137^c, in the end 80 plates 120, 121, and are held therein by means of screws 137^a, which pass through elongated slots therein, and are secured in the end plates.
- The uppermost link of the endless feeding chain 102, rests upon the uppermost portion of the squared or four-sided sprocket 170, on the shaft 164, while the lower portion of said chain engages the lowest portion of another four-sided squared sprocket 85 170^a, of the shaft 170^b, and which is similar in construction at this point to the shaft 164. The shaft 170^b, is preferably supported in journal boxes 170^c, movable in vertical guideways in the side plates 120, 121, and between 90 which and the upper ends of the guideways, are disposed springs 170^d, to permit of the sprocket 170^a, to rise against the influence of said springs, thereby easing the movement of the endless chain, as it moves to 100 bring the name and address plates or holders to the proper printing position. On the shaft 164, are seats or cradles 186, which have upwardly and outwardly extending sides 187, slightly tapered, so as to engage 105 the tapered sides, of the name and address holders inside of, but adjacent to the flanges 84, which sit outside of and adjacent to the bottom of the cradles 186. Also on said shaft 164, between the four sided or squared portion 170, is a flat portion 188, upon which the flat link portions of the conveyer chain 102 fit, and which portions cause the shaft 164 to act as a tumbler shaft or sprocket for the said chain, and the name and address 110 holders carried thereon. The lugs or extensions 85, travel against flange 137, which is continued over tumbler shaft 164.
- I desire to here explain that the size of the printing seat 170 is necessarily restricted 115 to the space required to print the address at the head, with spacing corresponding with the spacing of the letter, in order to simulate actual typewriting; therefore the address holder and seat have a restricted width. 120 Moreover it is evident that the unit of feeding movement is dictated by the width of the holders and their printing seat 170. Also the chain and address holders must in practice, accommodate themselves to the 125 130

strains due to the change from the vertical travel to the horizontal seat, and these strains are such owing to the small circle described by the flat seat portion, and the 5 necessity of making the seat, form a firm and solid printing bed, that special provision must be made to prevent jamming or the alternative of breaking. The proper movements of the chain and address holders 10 in the present machine are obtained perfectly by the yielding of the chain to the strains by reason of the springs 170^a, and contributing to the result also is the independent transverse movement permitted the 15 address holders on the chain in turning over the upper shaft, the holders not being positively connected with the chain.

The fact that the holders are not positively locked on the chain, makes it exceedingly 20 desirable, if not absolutely necessary, that said holders be operated or controlled independently of the feeding action of the chain, since otherwise they will either leave their seats by an outward, radial movement, or 25 they will become jammed. Hence I cause the upper shaft or seat and the holders, to mutually have a sprocket action independently of the sprocket action of the chain; and to this end, I have means whereby there 30 are shaft or seat members, and co-acting members on the holders for positively engaging each other. For the indicated purpose I utilize in the illustrated construction, the described members 84 that project rear- 35 wardly from each holder for contact with an adjacent holder, and these are engaged after the manner of sprockets, by the outer ends of the members 187, the members 84, being accommodated outside of the end surfaces 40 of 186^a (Fig. 30). Thus for convenience, the members 84 are caused to perform the double office of sprocket devices for the holders and protectors for the type faced matter in the holders.

45 It is to be understood that the term "address holders" means any form of printing block having separate type, or having solid cast, type faced matter.

Secured to the carriage D is a finger or 50 trip 189, which, when the pressure or printing roller 16, has passed over the type in the chase and has completed the printing of the name and address and also the date, and the carriage is further advanced, engages 55 one of the teeth or arms 159, of the wheel 157, and turns it one quarter of a revolution, bringing the next succeeding name and address to position for printing. Normally, 60 the toothed wheel 157, is locked against rotation by means of a detent 190, having a tooth 191, adapted to enter one of the four notches 158, formed therein, and the release of this detent is effected through the medium 65 of a trip or finger 192, also carried by the carriage, the arrangement being such that

said finger 192 which is located slightly in advance of the trip or finger 189, will first engage the detent and move its tooth 191 out of the notch 158, in the wheel 157, at, or approximately at a moment when the 70 trip or finger 189, engages one of the arms 159, of the wheel 157. The detent is pivotally supported on a stud 121^d, on a block 121^c, slideable under the influence of a screw 121^b, on the frame member 121, in opening 75 121^e and a spring 121^a, secured at one end to the detent, and at its other end to any convenient part of the bed or plate of the machine, serves to keep said detent constantly moved toward and in engagement 80 with the toothed wheel 157, so that its tooth may drop into the notches as they are successively brought into register therewith.

The described mechanism of Fig. 2^b, serves for adjusting the front or back side of the 85 four sided, rotatable name and address printing beds or seats. Mechanism has already been described whereby the shaft, supported by the carriage upon which the rotatable name and address printing seats, may be 90 raised or lowered slightly in a vertical direction, on either side of the machine, for the purpose of adjusting the height or position of the face of the name and address type, so that the impression may be identically the same on either the right or left 95 end margins of said name and address. In addition the mechanism shown in Fig. 2^b is for the purpose of slightly tipping or lowering the front or first line of said name 100 and address, or for tipping or lowering the bottom or last line of type, in said name and address holder, so that the printing or impression from the face of the type in each 105 name and address holder will correspond in every way, with the impression of the body 110 of the letter, the main form proper. This is accomplished by operating the thumb screw 121^b which shifts the pivot of the lever detent 191 in one direction or the other, causing it to occupy a position more or less inclined from vertical, when seated in its notch in the wheel 157, the adjustment thus 115 having the effect of tilting or slightly rocking the seat of the name and address holder very minute amounts for the purpose stated.

The fingers or trips 189 and 192, are loosely mounted on a shaft 187^a, secured in the side walls 15 of the carriage D, and extending upwardly from and preferably 120 made in one with said trips, is an arm 193, which bears against a rod 193^a, located above the shaft 187^a, and which serves to keep the trips in proper position to engage the detent 190 and arms 159 of the wheel 157 over 125 which they will pass as the carriage is moved forward. A torsional spring 194, on the shaft 187^a, one end of which is secured to the carriage frame and the other end to the upstanding arm 193, causes the latter to 130

be normally held against the rod, but will yield as the trips lift on passing over the wheel 157, during the return movement of the carriage. Thus, at each complete movement of the carriage D, a different name and address holder is brought into proper position to be impressed on the letter or the like.

After all the name and address plates or holders, contained in a magazine tray 87 have been fed to the endless chain 102, and it is desirable to remove such tray and replace it with another, containing a fresh supply, the feed belts or conveyers 92, are disconnected from their drive mechanism so as to permit of free and unobstructed movement thereof, thereby enabling the operator to bring the blocks or followers 95, 99^a, respectively, back and around the pulleys or rollers 93, out of the way of the tray. The means employed for effecting this disconnection of the belts or conveyers 92, from the drive mechanism, is clearly shown in Figs. 2 and 2^a, and comprises a cam block 195^a, located at one end of a rod 196^a, and having at its other end a finger piece or button for manipulating it. The cam block is located above the pawl 175, and normally out of engagement with a finger or extension 175^a, projecting from or forming part of said pawl, but when the rod 196^a, is moved to bring the cam block into engagement with said finger 175^a, it will cause the pawl to be lifted out of engagement with the teeth of the ratchet wheel 173, thus effecting disconnection with the belts or conveyers 92.

The inking ribbon 195, is disposed above the chase 5, and date holder 196, and is carried on transversely arranged rolls or spools 197, 198, upon which it is alternately wound, mechanism being provided for intermittently moving the ribbon over the type at or near the completion of each movement of the carriage D. This mechanism is clearly illustrated in Figs. 3, 4 and 5, where it will be seen that the spool or roll is supported at one end on the outer free end of a spring actuated plunger or pin 199 (which may be moved backwardly against its spring 199^a to permit of the removal or insertion of the spool or roll) and at the other end it is fixed to a stub shaft 200, which extends through the frame and carries on its outer end a ratchet 201, pinned or otherwise secured thereto. A sleeve 202, is loosely mounted on the shaft 200, and disposed between the end of the roll or spool 197, 198, and the ratchet 201, and to this sleeve is secured a disk or plate 203, having a pawl 204, to engage the teeth of the ratchet 201. A gear wheel 205, is also secured to the sleeve 202, which meshes with the teeth of a rack 206, which moves in an elongated groove 207, provided in the frame, said

rack being also provided with a tooth 206^a, adapted to be engaged by a pin 208, projecting inwardly from the walls 14, 15 of the carriage D. Thus, as the carriage is moved in one direction or the other the pin 208 ⁷⁰ will engage the tooth 206^a, moving the rack and rotating the pinion and disk or plate 203, which, through its attached pawl 204, will turn the spool or roll and wind thereon the ribbon to a more or less extent. ⁷⁵

The extent of movement of the rack 206, is controlled by a threaded pin 209 adapted to pass through a tapped perforation 210, in the frame and to enter and contact with one end of a groove 211, formed on the inner face of the rack 206. A spring 212 is arranged within each of the grooves 207, one end of which is fastened to the frame and the other end to the rack, thus the rack after being advanced by the pin 208, on the carriage, and when the latter is moved in the opposite direction, will be brought back to the initial position where the end wall of its groove will be engaged by the pin 209.

The rack may be moved forward against ⁹⁰ the tension of its spring, and the pin 209 may be inserted in any one of the tapped perforations 210, so that the pin 208, on the carriage D, may be caused to engage the tooth 206^a, at any predetermined point, ⁹⁵ thereby giving more or less travel to the rack and consequently controlling the amount the ribbon shall wind at each movement of the carriage.

There are two pins 208, one for the spool 100 or roll 197, and the other for the spool or roll 198, and it will be understood, of course, that one of the pins will be thrown out of operation when the other is in use. Each of the pins 208, has a reduced stem portion ¹⁰⁵ 208^a, which passes through a perforation in the wall 15, and upon the outer end of which is secured a milled head 213, having on its inner face, a pin 214, adapted, when the pin 208 is in operative position to enter an opening in the wall 15, but when in inoperative position said pin 214, is withdrawn from the opening, and by partially rotating the button or finger piece 213, is caused to rest against the wall 15, thereby keeping the pin ¹¹⁰ 208 also withdrawn.

The rack 206 is held in proper relation to the frame by a plate 215, which is secured to the frame by screws 216, and has at its outer end a spring plate 217, having an inwardly ¹²⁰ projecting pin 218, on the end thereof, said pin being adapted to enter a slot or groove 219, in the tooth 206^a of the rack 206, when the latter is brought into register or line therewith, as shown to the right of Fig. 3. ¹²⁵ This is for the purpose of placing the tooth 206^a, in a position to be free from contact by the pin 208, as the carriage is moved, thereby preventing any movement whatever of the rack 206, and it will be observed that ¹³⁰

the pawl 204, to the right of Fig. 3, is lifted out of engagement with the ratchet 201, in order that the spool or roll 198, at that end of the machine may be free to unwind the ink ribbon. A spring 220 secured, respectively, to the disk or plate 203, and pawl 204, serves to keep the latter either in engagement or disengagement with the ratchet 201.

In order to insure that the carriage D, shall make a complete movement in both directions, I provide a rack 221, which is secured to the inside of one of the side members 3, of the machine, and upon the carriage D, I provide a spring controlled pawl 222, to engage said rack and the said pawl when resting at a point beyond either end of the rack will, through the medium of a spring 222^a, assume a vertical position, but, when the carriage is moved in one direction or the other the pawl will ride up over the end of the rack and engage the teeth thereon, assuming an inclined position, as clearly shown in Fig. 3. Thus, any attempt to move the carriage back, after an advance movement has taken place in either direction, will be frustrated, and a completion of the movement thereof will be necessary to release the pawl 222.

The holder 196, for containing the date is located immediately behind the endless chain 102, and is adjustably secured by shouldered screws 224, to a bracket 225, supported by the side members 3 of the machine. The bracket 225, is provided with lateral extensions 226, having elongated slots 226^a, to receive shouldered set screws 227, which enter threaded openings in the side members 3, thereby permitting of longitudinal adjustment of the bracket 225. The holder 196, has lugs or projections 223^a, in which are tapped perforations to receive adjusting screws 223^b, which rest upon the upper edge of the bracket 225, and by means of which the holder 196, may be adjusted to bring the type therein to a true level with the type 6 in the chase 5. Slots 223^a, in the bracket 225, (dotted lines Fig. 12) through which the shouldered screws 224 pass into tapped openings in the holder, permit of this vertical adjustment.

In a machine of this character, it is desirable, and even necessary to provide safety devices for the purpose of preventing unwarranted operation thereof by unskilled persons, or those ignorant of the manner in which they should be handled, attempts of this kind frequently putting the machines out of commission. To avoid this, means are provided for locking the machine against operation, so that when not in use the printing carriage and other movable parts of the machine are securely locked and cannot be moved until positively released. The means for accomplishing this comprises a spring actuated bolt 223^c, which passes through an

opening in the side wall 15, of the carriage D, and enters an aperture in the side 3, of the bed or frame of the machine. The bolt has a reduced stem portion 224^c, on which is located a coiled spring 225^c, adapted to keep the bolt thrust forwardly, and on the outer end of said stem is secured a button or finger piece 226^c, upon the inner face of which is a pin 227^c, adapted to enter an aperture in the adjacent side wall 15, of the carriage. A pull exerted upon the button or finger piece will withdraw both the bolt 223 and pin 227 from their respective apertures, and by giving a slight turn to the button or finger piece 226, it will bring the pin 227 in position to bear against the wall 15, thereby keeping the bolt withdrawn and effecting the release of the carriage, until such time or times as the pin 227, is again brought into register with the aperture in the frame 3, when the spring 225 will thrust the bolt back into the aperture in the side wall 3, again locking the machine.

A signaling mechanism is provided for giving audible indication that the name and address holders or plates 79 have all, or approximately all, been fed from the delivery magazine tray to the machine, and that the receiving tray has also been charged to its capacity with the ejected holders or plates. This mechanism is illustrated diagrammatically in Figs. 31 and 32 and consists of an electric bell b, located at any convenient part of the stationary frame work of the machine and receiving its current from any ordinary form of battery, as at X. Contact pieces c, d, are arranged at or near the discharge end of the delivery magazine tray 87, and similar contact pieces e, f, are located at or near the front end of the receiving magazine tray 87^a, and all of which are properly insulated from the frame or bed and are in circuit with the bell b, and battery X.

Under the plate 95, or, as herein shown, the plate 99^a is a contact strip g, properly insulated therefrom and which, when the plate 99^a and name and address holders or plates in front of it, are moved forward by the belts or conveyers 92, is adapted to bridge the contact plates c, d, and close a circuit leading to the bell, thereby giving audible indication that the tray 87, is empty, or nearly empty, of name and address holders or plates; and upon the underside of, and properly insulated from a block or plate 95^a, usually placed in the receiving tray 87^a, at a point where the first name and address holder or plate is ejected therein, is a contact strip g', for bridging the contact strips e, f, as in Figs. 1 and 32, the strip g' is omitted from Fig. 12. This will close another circuit leading to the bell and give a similar indication that the tray 87^a, is filled

or approximately filled with ejected holders or plates. The circuit for the delivery tray 87, starting from the battery X, is wire h, contact piece e, contact strip g, contact piece d, wire i, and through the bell b, back to the battery; and the circuit for the receiving tray is from the battery X, through wires h, k, contact piece e, contact strip g'; contact piece f, wires l, m, i, and through bell b, back to battery.

The chase 229 illustrated in Figs. 24 and 34, is adapted to fit in the chase 5, wherein it may be locked with ordinary printers' quoins as previously set forth. It is formed 15 with a plurality of parallel grooves 229^a, similar in every respect to the grooves 80, in the name and address holders or plates 79, and into which are set up the type forming the body portion of the letter or other matter to be impressed on the paper. One end of the chase is cut away, as at 230, to provide a cavity or recess for the reception of a block 231, having on its face the salutation, herein shown as "Gentlemen." This 20 block is also locked in position by quoins, or in any other desired or convenient manner. On the side of the chase where the type is inserted is a plate 232, having elongated slots 233, to receive locking screws 234, which pass therethrough and enter threaded openings in the body portion of the chase. When the letter or other matter 25 is being set up, the plate is lowered to the position shown, leaving the grooves 229^a, free and unobstructed to receive the type, but when the chase has been primed with the proper matter, the plate is again raised to cover the ends of the grooves and thus lock the type in place therein.

40 Instead of fixing the salutation holder 231, in the cavity 230, of the chase 229, I may provide at the lower right hand corner of the chase 6, as viewed in Fig. 10, a mechanism for automatically changing the salutation from "Dear Sir," as shown in Fig. 10, to "Gentlemen" and back again, when the letter impressed is to be addressed to either an individual, firm or corporation, and this 45 mechanism is operated at proper times, preferably through the name and address holders or plates as they are moved into printing position. This mechanism is clearly illustrated in Figs. 10, 12 and 27^a, and comprises a roll 235, journaled in a bracket 236, and having flattened sides on which the various salutations are placed. The bracket is secured in any desired or convenient manner to the frame of the machine, and, as shown in Fig. 10, fits into a recess 237, provided in the chase 6, at a point contiguous to the name and address operating mechanism, and, as the latter is moved to successively bring holders or plates 79, into printing position, the holders which are provided with a lug or teat 238 or 239, will en-

gage three-toothed star wheels 240 or 240^a, secured to one end of a shaft 241, which passes through the bracket 236, and has at its opposite end a gear wheel 242, adapted to mesh with the teeth of a pinion 243, secured to the projecting end of a shaft 244, on which the flattened roll 235, is mounted. A detent, in the form of a flat spring 245, is secured to the bracket 236, and its free end bears against one of the flattened surfaces of the roll 235, thus serving to lock and keep the latter maintained in position after each partial rotation.

In the construction and arrangement shown, I have made provision only for the salutation "Gentlemen" and "Dear Sir" and have therefore shown a four-sided roll on which is alternated the salutations mentioned, but it will be apparent to those skilled in the art that the flattened sides of the roll may be increased to include the salutation "Dear Madame" in which event the star wheels 240 and 240^a, will be proportionately increased to make the desired and proper change at the required time. The star wheels 240, 240^a, are placed side by side on the shaft 241, and, as will be observed by reference to Figs. 12, 21 and 21^b, the holders or plates 79, containing the names and addresses where a change of salutation is necessary, are provided with the lugs or teats 238 or 239, which, when moving into printing position, will engage one of the teeth of one or the other of the star wheels and give to the flattened roll 235, a partial rotation, thereby operating it to change from one salutation to the other. Each lug or teat 238, 239, is, of course, arranged to travel in true vertical alinement with its coacting star wheel, and it may be made integral with the holder or plate 79, or it may be made similar in shape to the body portion 82, 82^b, of the type 82^a, and fitted into a groove 80, of the holder or plate 79.

In Fig. 33 is shown a mechanically operated signal that may be employed instead of the described electrical signal. The gong b' is supported from shelf 87^b, and is adapted to be struck by clapper b², mounted on a bracket b³; a projecting arm b⁴, of said clapper is actuated in one direction by a spring b⁵, and is adapted to be struck and moved against the tension of said spring by the corner b⁶, of the follower member 99^a. To lock the trays 87, 87^a in place in the machine, one side of each tray is formed with a hole 230^a, (Fig. 22) and pins 228^a and 229^b (Fig. 2) fitted for axial movement in the plate 128. By withdrawing said pins from the holes 230^a in the trays, the latter may be removed from the machine frame.

I claim:—

1. In a printing machine for the purpose described, a chase holding a main type sur-

- face, a printing or pressure roll coating therewith to print by rolling pressure thereon, delivery and receiving trays removably supported by the machine and 5 adapted each to interlock with a series of independent form-holders, means for successively removing holders from said delivery tray and conducting and seating the same in the printing plane of said main type surface, whereby the impression may be taken from the latter and said seated holder in 10 one operation, and means for introducing said holders, after the impression, into said receiving tray.
- 15 2. In a printing machine for the purposes described, having in combination a bed or table, a chase for holding the type forming the matter to be impressed, an inking ribbon disposed above and movable over the face 20 of the type, a carriage having a printing or pressure roll adapted to revolve upon and over the type, means for throwing said printing or pressure roll into and out of operative position, means comprising removable 25 magazine trays adapted respectively to contain type-surface holders to be delivered to the machine and to receive said holders as they are ejected therefrom, and means for automatically and successively moving 30 said type holders from the one removable magazine tray through the bed into printing position in alinement with the chase and for thereafter ejecting them into the other magazine tray.
- 35 3. In a printing machine for the purposes described, having in combination a bed or table, a removable chase for holding the type forming the matter to be impressed, a carriage having a printing or pressure 40 roller adapted to be moved over and revolved upon the type, adjustable bearings for said roller having spring cushions thereunder, means for throwing said roller into and out of operative position, portable containers 45 constituting magazine trays adapted respectively to contain name and address holders to be delivered to the machine and to receive the name and address holders as they are ejected therefrom, and means for 50 automatically and successively moving said name and address holders directly from the one magazine tray through the bed into printing position and for thereafter ejecting them into the other magazine tray.
- 55 4. In a printing machine for the purposes described, having in combination a bed or table, a type-holding chase for containing the matter to be impressed, an auxiliary holder for containing the date, a name and 60 address mechanism disposed between them, a carriage having a printing or pressure roller adapted to be revolved over and upon the type, means for throwing said printing or pressure roller into and out of operative 65 position, magazine trays adapted respec-

tively to contain name and address holders to be delivered to the machine, and to receive the same after ejection therefrom, and means for imparting intermittent motion to the name and address mechanism whereby the 70 holders are successively brought into printing position.

5. In a printing machine for the purposes described, having in combination a bed or table, a type-holding chase for containing the matter to be impressed, an auxiliary holder for containing the date, a name and address mechanism disposed between them, a carriage having a printing or pressure roll adapted to be revolved over and upon the 80 type, means for throwing said printing or pressure roll into and out of operative position, magazine trays, adapted, respectively, to contain name and address holders to be delivered to the machine and to receive the 85 same after ejection therefrom, means for imparting motion to the name and address mechanism, whereby the holders are successively brought into printing position, and means for afterward ejecting them from the 90 machine.

6. In a printing machine for the purposes described, having in combination a bed or table, adjustable chases or holders for containing the matter to be impressed including the salutation and date, a ribbon disposed over the face of the type, a carriage having an eccentrically supported printing or pressure roll normally maintained out of operative position and adapted to be revolved over 100 and upon the type, a signature roll also journaled in said carriage, and adapted to impinge on or to lie adjacent to the printing or pressure roll, means for throwing the signature roll into and out of operative 105 position, whereby rotation is imparted thereto, a separate inking means for the signature roll, magazine trays adapted, respectively, to contain name and address holders to be delivered to the machine and to receive the same after ejection therefrom, and a feed mechanism for automatically and 110 successively lifting the name and address holders into printing position.

7. In a printing press for the purposes described, comprising a bed or table, means for holding the type forming the matter to be impressed including the date, a carriage having a printing or pressure roll adapted 115 to revolve upon and over the type, means for throwing said printing or pressure roll into and out of operative position, a delivery magazine tray adapted to contain name and address holders to be delivered to the machine and a receiving tray to receive the 120 name and address holders as they are ejected therefrom, locking devices arranged at one end of the magazine trays whereby the holders are held in assembled position and against displacement, means for automati- 13

- cally releasing the locking devices on the delivery tray, and means for automatically bringing the name and address holders successively into printing position, and for afterward ejecting the same.
8. In a printing press for the purposes described, comprising a bed or table, type holding means for containing the matter to be impressed including the date, a carriage, a printing or pressure roll loosely mounted on eccentric bearings arranged in said carriage and adapted to revolve upon and over the type, means for turning the eccentrics in either direction, whereby the printing or pressure roll is brought in contact with the type, or lifted away from it at definite points, a delivery magazine tray adapted to contain name and address holders to be delivered to the machine, a belt or conveyer, a follower arranged to move with said belt or conveyer and having a slip connection therewith and adapted to engage the rear-most name and address holder, whereby they are bodily and intermittently moved toward the point of printing, said slip connection comprising a hollow block into which the belt is passed and an adjustable rod arranged within said block and adapted to frictionally engage the belt or conveyer, whereby the intensity of the grip upon the belt or conveyer may be regulated, a receiving tray to receive the name and address holders after the same have left the printing point, locking devices arranged at one end of the magazine trays whereby the holders are held in assembled position and against displacement, means for automatically releasing the locking devices on the delivery tray, and means for automatically bringing the name and address holders successively into printing position, and means for afterward ejecting the same.
9. In a printing machine having a bed, and a pressure roll mounted for traverse movement over the bed, an address printing means comprising separate address forms and a carrier chain for said forms, said chain serving to carry the forms to the plane of movement of the pressure roll for printing.
10. A magazine tray for receiving name and address holders comprising a frame consisting of end and parallel side members, each member having on its inner side a rib or rail, projecting slightly beyond one end thereof and extending approximately along its entire length and adapted to receive the recessed ends of the name and address holders, and locking devices adapted to keep said holders in assembled position therein.
11. In a printing machine, the combination of a bed and a carriage having a traverse movement on said bed, address holders, a delivery tray for said holders, a receiving tray for the holders, a conveying means for

carrying the holders from the delivery tray to printing position and then returning them to the receiving tray, means for discharging the holders in succession from the delivery tray, means for ejecting the holders from the conveying means to the receiving tray, and operating means for the said discharging and ejecting means, said operating means being actuated automatically and in predetermined relation to the movement of the carriage.

12. In a printing machine, the combination of impression means including a carriage, address forms, with respect to which the carriage moves in printing, means for carrying the said forms to and from the printing position, means for discharging the forms to the carrying means, means for ejecting the forms from the carrier, and operating means for the said discharging and the said ejecting means, and a member actuating in common both the discharging and the ejecting means.

13. In a printing machine, the combination with a bed and an impression roll, of which one is mounted for traverse movement; of a signature roll, a shaft eccentrically mounting said signature roll and having a rock arm to change the eccentricity of the roll, and a track on the bed for contact-95 ing with said arm, said track being adjustable to register the signature, with the desired point on the sheet.

14. In a printing machine, a type bed, a pressure roll, means for feeding paper between the roll and the bed, means for effecting relative movement of the roll over the bed, and means for regulating the amount of paper fed between the roll and the bed before the relative movement of roll and bed brings the roll into printing coöperation with the type on the bed.

15. In a printing machine, a type bed, pressure roll, means for feeding paper between the roll and the bed, means for effecting relative movement of the roll over the bed, means for effecting relative movement of the roll transversely of the bed, on to and off of the same, and means for regulating the time of engagement of the roll with the bed to determine the amount of paper feed in advance of the printing operation.

16. In a printing machine, a type bed, a pressure roll, means for feeding paper between the roll and the bed, means for effecting relative movement of the roll over the bed, an eccentric on the roll and a track on the bed for coöperation with the eccentric for effecting relative movement of the roll transversely of the bed, on to and off of the same, and means for adjusting the position of the track to regulate the time of engagement of the roll with the bed for determining the amount of paper feed in advance of the printing operation.

17. In a printing machine, a type bed, a pressure roll, means for feeding paper between the roll and the bed, means for effecting relative movement of the roll over the bed, an eccentric on the roll and a track on the bed for coöperation with the eccentric for effecting relative movement of the roll transversely of the bed, on to and off of the same, and means for adjusting the length of the track to regulate the time of engagement of the roll with the bed for determining the amount of paper feed in advance of the printing operation. 5
18. In a printing machine the combination of a machine frame, a letter form stationarily mounted thereon, a plurality of independent address forms, means for moving said address forms successively into alinement with said stationary form, a plurality of 15 salutation forms, means controlled by the address forms for moving the required salutation form into alinement with the letter and address forms, a single inking ribbon carried by the machine frame and extending across the face of the letter, address and salutation forms, and automatic means adapted to traverse said ribbon after the forms are alined whereby the body of the letter, the address and the salutation are 25 printed from said ribbon. 30
19. In a machine of the kind described, the combination of a roller platen and a bed forming a printing couple, a permanent form on the bed, a series of disconnected changeable forms, an endless conveyer operating to conduct such changeable forms into predetermined printing position with respect to said permanent form, and means whereby such changeable forms 35 are introduced into and discharged from the endless conveyer. 40
20. In a machine of the kind described, a roller platen and bed, forming a printing couple, a main form on the bed, a series of 45 separate changeable forms, an endless conveyer for advancing same successively into printing position adjacent said main form, and guide means for holding said changeable forms in position on the conveyer to be 50 advanced by the latter. 55
21. In apparatus of the class described, the combination with a bed and platen, a series of changeable forms, an endless conveyer not connected with said forms and adapted to receive and advance them to the printing plane of said bed and platen, and rail members adjacent said conveyer serving to maintain the forms in seated position thereon during their travel to and 60 from said printing plane. 65
22. In a machine of the kind specified, a roller platen and a bed, adapted to support a permanent form, a series of changeable forms, a removable frame, and a conveyer adapted to advance said changeable forms 65
- into the printing plane of the permanent form, said conveyer being carried on the removable frame and being thereby interchangeable with other conveyer mechanism. 70
23. In a machine of the kind described, a main frame, a roller platen and bed, and a removable frame, a permanent form on the bed, a series of changeable forms, having a seat supported by said removable frame and adapted to hold said forms in the printing plane of the roller platen and main form, means on said removable frame for successively advancing the changeable forms 75 into said seat, and means whereby such advancing means is operated automatically between impressions. 80
24. In a machine of the kind described, a roller platen and a bed adapted to support a main form, a series of separate changeable forms, a magazine for the latter, and means adapted for connection with the magazine for successively conducting said forms therefrom into the printing plane of the main form, and provisions whereby such conducting means may be moved laterally 85 with respect to the main form to aline the changeable forms therewith. 90
25. In a machine of the kind described, a roller platen and a bed adapted to support a main form, a magazine of separate changeable forms, means constructed for connection with the magazine, adapted to conduct said changeable forms therefrom successively into the printing plane of the main form, said means being adjustable toward 95 100 and from the said printing plane and parallel thereto. 105
26. In a printing machine of the kind described, a roller platen and main form, a series of changeable forms, means for supporting successive members of the series in the printing plane of the main form and a frame for said supporting means which is adjustable toward and from the said plane, and means for automatically moving the 110 changeable forms into and out of the said supporting means. 115
27. In a machine of the kind set forth, a roller platen, a main form, and a changing-form-mechanism comprising a pair of side members 120 and 121, a magazine in communication therewith, and means whereby successive changeable forms are advanced between said side members into the printing plane of the main form, and means for laterally adjusting the said side members. 120
28. In a machine of the kind specified, a roller platen and bed, a series of separate changeable forms, a conveyer chain for conducting the same to the printing plane, and stationary means for confining the forms in the chain. 125
29. In a machine of the kind described, a roller platen and main form, and changeable form mechanism comprising a series 130

- of forms, a seat to hold the same in the printing plane of the main form, means whereby the plane of said seat can be angularly adjusted with respect to the printing 5 plane of the main form, and means for automatically advancing said forms successively into said seat.
30. In a printing machine, form-changing mechanism comprising a rotary body, a series of independent address forms successively supported thereon in the printing plane, means for intermittently rotating the body, and means for adjusting the angular position of which such body assumes between its intermittent rotations.
31. A printing machine, comprising a roller platen and a main form constituting a printing couple, a changing form in the printing plane of the main form, and a further form suitable for printing a signature, said forms being organized to print on the same sheet in a single reciprocation of the moving member of the couple, in combination with means for preventing reversal of such reciprocation on less than a full stroke of the reciprocating elements of the said couple.
32. In a machine for printing imitation type-written letters, a roller platen and main form, a changing form, an ink ribbon covering such forms, and means for varying the printing position of the changing form with respect to the main form, in combination with a signature printing form independent of the ink ribbon, means for adjusting the operating position thereof and means whereby said forms are automatically impressed upon the paper sheet in a single operation.
33. In a machine of the kind described, the combination of a roller platen and a main form for printing the body of a letter, a signature printing mechanism, and controlling means therefor comprising a track and means for adjusting the position thereof with reference to the said main form and roller platen.
34. In a machine for making imitation type-written letters, the combination with a roller platen and type form forming a printing couple, of a throw-off device controlling the coaction therebetween and comprising a rail device which is longitudinally extensible to lengthen or shorten the extent of such coaction.
35. In a machine for making imitation type-written letters, a changing form mechanism comprising a magazine and means for successively advancing forms from such magazine into printing position, a main form the plane of which coincides with the said printing position, a support for said main form independent of said changing form mechanism and comprising a series of adjustable bearings, means for removably clamping the said main form thereon, and

a roller platen coacting in one operation with said main form and the changeable form in its said printing position.

36. In a machine for making imitation type-written letters, the combination of a flat bed, a trackway, a carriage thereon having a roller platen, a throw-off device for controlling the coaction of said bed and platen, and means for adjusting the position of the platen in its carriage comprising a screw 27 and a locking pin 34 therfor.

37. In a machine for making imitation type-written letters, the combination of a flat bed and roller platen, bearings for the latter adapted to adjust it to the plane of the bed, a throw-off device for said platen and adjustable rails for operating the same, the adjustment of the rails providing auxiliary means to adjust the platen to the plane of the bed.

38. In a machine of the kind described comprising a roller platen and main form constituting a printing couple, a changeable form having printing position in the plane of the main form, means for changing the changeable form and substituting others in place of it, a cam-member for operating the changing means, said cam member serving to transmit the reciprocating movement of the movable member of the printing couple to said form changing means.

39. A machine of the kind described comprising a main form, a changeable form, a roller platen coacting with both, and a removable magazine holder for the changeable forms comprising an open frame interfitting with said changeable form and from which said forms are removable only at the end, and means adapted for communication with the said end for conducting the forms therefrom to the printing plane of the roller platen.

40. A machine of the kind described comprising a main form, a roller platen, and a changeable form mechanism, the latter comprising a magazine holder removably supported in the machine, machine-driven means for advancing the changeable forms along and out of one end of the magazine and conveyer mechanism which removes each form from the magazine to the printing plane of the main form.

41. A machine for making imitation type-written letters comprising a main form and roller platen, a series of changeable forms and a removable magazine holder therefor having means for confining the forms therein, and means for conducting the forms from the magazine to the printing plane of the platen, said latter means coöoperating with the magazine to release the forms therefrom.

42. A machine of the kind described comprising a main form and roller platen, a series of changeable forms and means for

changing the latter forms comprising a removable magazine open along one side, a machine-driven part adapted to operate through said open side to advance the 5 changeable forms along the same, and a conveyer for successively removing said forms to the printing plane of the roller platen.

43. In a machine of the kind described, a 10 main form, a roller platen, a magazine of changeable forms and means for successively placing the latter forms in the printing plane of the roller-platen, said changeable forms each consisting of a type-form surface 15 and a holder or support therefor provided with a pair of lugs at each end, side members engaging said lugs to guide the same to printing position, and means in the magazine also engaging said lugs to guide 20 the same therein.

44. A machine of the kind described, comprising a stationary flat bed having a main type form thereon and an automatically changing form, and a reciprocating carriage 25 carrying a roller platen for both said forms, in combination with rack and pawl members, one of them mounted on the reciprocating carriage and the other secured to said stationary bed and adapted to prevent reverse 30 movement of the carriage on less than a full throw thereof, the said rack member being disposed parallel with the path of movement of the carriage and extending alongside of said bed.

45. In a machine of the kind described, a 35 main form of typewriter type, an ink ribbon covering the same, a roller platen coacting therewith, means for guiding the paper sheet around the roller platen and said 40 platen making more than a single revolution while engaged with said sheet, a supplementary form operating on the sheet against the roller platen, independent means for inking said supplementary form, and means 45 whereby the impression pressure of said supplementary form may be varied independently of the platen and said main form.

46. In a machine of the kind described, a 50 bed supporting a main form, a roller platen cooperating with the latter to print upon a paper sheet and making more than a single revolution in contact with said sheet, and a printing roll cooperating intermittently with the roller platen, in combination with means 55 for automatically locking said roll during its idle period.

47. In a machine of the kind described, the combination with a main form, a roller platen and means for feeding a paper sheet 60 thereto, said roller platen making more than a single revolution in contact with the sheet,

a printing roll acting on said sheet while in motion from the printing plane of the main form, a shaft for such roll, and means whereby the printing roll can be moved to 65 different positions along the shaft.

48. A machine of the kind described, comprising a ribbon-covered main form of typewriter type, a roller platen, an intermittently-acting signature printing roll, independent inking means therefor, and means for automatically advancing said roll bodily to printing position, said means comprising a lock for said roll, which is released by its 70 said advancing movement. 75

49. A machine for making imitation type-written letters, comprising main and automatically changing forms, a ribbon for these forms, a separately inked form, a reciprocating carriage and a roller platen thereon 80 coacting with all said forms, in combination with a plurality of adjustable track members and parts moving with said carriage adapted to engage said track members to respectively control the impression pressure upon 85 each of said forms.

50. In a machine of the kind described, a main form, an automatically changeable form and an ink ribbon covering both forms, means for conducting a paper sheet to said 90 ribbon, a roller platen coacting with said forms and making more than a single revolution in contact with the paper, a supplementary form operating on said sheet against the platen, said supplementary form being 95 adjustable laterally of the said main form, and means for changing the impression pressure of said supplementary form.

51. A machine for printing imitation type-written letters, comprising a bed, a 100 main frame of typewriter type thereon, an ink ribbon covering the type surface, means for guiding a paper sheet to such ribbon and a roller platen cooperating therewith to print the body of the letter and making 105 more than a single revolution in engagement with said sheet, in combination with a supplementary form cooperating with said roller platen independently of the ink ribbon and suitable for printing a signature 110 on said sheet in the same operation that prints the body of the letter, and means for adjusting said supplementary form to alter the position of its impression longitudinally 115 and crosswise of the paper sheet. 115

In witness whereof I have hereunto signed my name this 25th day of October, 1910, in the presence of two subscribing witnesses.

WALTER WRIGHT.
